US0D1072294S

(12) **United States Design Patent** (10) **Patent No.:** **US D1,072,294 S**
(45) **Date of Patent:** **** Apr. 22, 2025**

(54) **LENS MODULE FOR AUTOMOTIVE LAMPS**

(71) Applicants: **Hyundai Motor Company**, Seoul (KR); **Kia Corporation**, Seoul (KR)

(72) Inventors: **Chang Hoon Choi**, Suwon-si (KR);
Dai Sung Kim, Gunpo-si (KR);
Byeong Ho Jeong, Yongin-si (KR);
Won Suk Kang, Hwaseong-si (KR)

(73) Assignees: **Hyundai Motor Company**, Seoul (KR); **Kia Corporation**, Seoul (KR)

(**) Term: **15 Years**

(21) Appl. No.: **35/519,914**

(22) Filed: **Jul. 27, 2023**

(80) **Hague Agreement Data**

Int. Filing Date: **Jul. 27, 2023**

Int. Reg. No.: **DM/231716**

Int. Reg. Date: **Jul. 27, 2023**

Int. Reg. Pub. Date: **Feb. 2, 2024**
